UNITED STATES PATENT OFFICE.

LEO E. SCHOENFELD, OF TAMPA, FLORIDA, ASSIGNOR TO JAMES S. KIRK & COMPANY, OF CHICAGO, ILLINOIS, A CORPORATION OF ILLINOIS.

DESIGN FOR A SOAP CAKE.

Application filed November 27, 1925. Serial No. 15,561. Term of patent 14 years.

To all whom it may concern:

Be it known that I, LEO E. SCHOENFELD, a citizen of the United States, and a resident of the city of Tampa, county of Hillsborough, and State of Florida, have invented a new, original, and ornamental Design for Soap Cake, of which the following is a specification, reference being had to the accompanying drawing, forming part thereof.

Fig. 1 is a face view of the smiling side of a soap cake, showing my new design.

Fig. 2 is a side view thereof, and

Fig. 3 is a face view of the opposite or crying side of the same.

I claim:

The ornamental design for a soap cake as shown.

LEO E. SCHOENFELD.
